LAMP SUPPORT WITH ROTATABLE APERTURED PLATE, INCLUDING A RECESSED SUPPORTING HOOK

George E. Eckert and William K. McGinty, Fort Atkinson, Wis., assignors to Moe Brothers Manufacturing Company, Fort Atkinson, Wis., a corporation of Wisconsin

Application April 30, 1947, Serial No. 744,976

14 Claims. (Cl. 240—52.1)

1

This invention relates to improvements in portable lamps and the like.

It is a primary object of the invention to provide a novel and simple lamp or like appliance of virtually universal application. A lamp made in accordance with the present invention has a special base whereby it may be permanently mounted on a wall or elsewhere; it may serve as a "pin-up" lamp; it may be set on a table or other support; it may be manipulated by hand; or it may be clipped to the back of a chair or some other support of that type. It is particularly adapted for use with "spot" bulbs such as are used for show window lighting and for special infra red or ultra-violet radiation.

In all positions and mountings of the base, the socket is adjustable to a variety of angles and the provision of a novel and simplified pivotal connection, permitting the adjustment of the socket and its retention in adjusted position, is another object of the invention.

Still other objects will be apparent from the following disclosure.

In the drawings:

Fig. 1 is a view in side elevation of a lamp embodying the invention.

Fig. 2 is a view taken in section on line 2—2 of Fig. 1.

Fig. 3 is a bottom plan view of the lamp.

Fig. 4 is a view taken in section on the line 4—4 of Fig. 1.

Fig. 5 is a view fragmentarily illustrating in side elevation the lamp as it appears when clipped to a chair back or the like.

Fig. 6 is a detail view taken in transverse section through the lamp base and swiveled mount.

The lamp base 10 comprises a hollow shell. It is provided near one end with an upwardly opening slot at 11 (Figs. 3 and 4) through which project the tongues 12 and 13 of standard 14. The tongues are flanged in opposite directions and preferably welded interiorly to the base as best shown in Fig. 3.

The standard 14 may comprise a single ply sheet metal support and it may, if desired, be convoluted or ribbed as best shown in Figs. 1 and 4 for stiffening or ornamentation. Near its upper end it is provided with an aperture for the pintle 15 upon which the shell 16 for electrical socket 17 is pivoted. The shell has a slot at 18 which closely receives the sheet metal standard 14. Within the shell a spacing sleeve 19 is threaded on the pintle bolt 15 and fits between the interior of the shell and one side face of the standard 14. The other side face of the standard 14 is engaged

by one arm of an angle bracket 20 connected with lamp socket 17 and having an aperture through which the pintle 15 passes. By reason of the close fit of the socket within shell 16 and the engagement of the angle bracket on pintle bolt 15, the socket is held against movement respecting the shell.

The angle bracket 20 further serves as one plate of a friction clutch for maintaining the shell and socket in angularly adjusted position on the pintle bolt 15. The compression spring 21, threaded upon the pintle bolt 15 and confined between nut 22 and bracket 20, urges the bracket into face contact with the standard 14, whereby friction between these parts holds the socket and its shell in any position of pivotal adjustment.

Forwardly of the standard 14, there is welded or otherwise fastened to the interior of the base 10, a boss-forming member 24 with a flat bearing surface at 25 through which extends a bolt 26. Held by bolt 26 to boss-forming member 24 is a mounting element 27 which preferably comprises a disk. It is preferably so located that its periphery is substantially tangent to both sides 25 and one end of base 10, as best shown in Fig. 3. The center of the disk may be embossed inwardly as shown at 28 to receive the bolt 26 and bear against the surface 25 of member 24.

This disk is provided with a marginal and apertured tab at 29 and keyhole slots 30 and 31, one of which is preferably near the tab and the other one opposite the tab. The disk is also cut away to provide an opening at 32 adjacent which there is an inwardly turned ear 33 to which a spring clip or arm 35 is pivoted by means of rivet 36. In its retracted position, the spring hook 35 lies substantially in the plane of the mounting element or disk 27 and within the cavity of the base where it moves around the boss 24 as the mounting element is rotated on its pivot 26.

The lamp may be used on a table, desk or other horizontal surface in the manner shown in Fig. 1, the position of the bulb in the socket being shown in broken lines.

For use in some temporary wall position as a "pin-up" lamp, the disk 27 is rotated slightly clockwise from the position shown in Fig. 3 to bring the keyhole slot 31 to the vertical center line. Thereupon such slot may be engaged with any suitable screw, nail or other hanger.

For permanent mounting, the keyhole slot 30 may be engaged over the head of a screw or nail or the like. Rotation of the entire base and lamp respecting disk 27 for 180 degrees from the position shown in Fig. 1 will expose the tab 29

which will then project over the end margin of the inverted lamp base. A nail or screw is driven through the aperture of the tab to complete the permanent attachment of the disk 27 to the wall and the entire lamp is then rotated back to the relative position shown in Fig. 3, whereupon the mounting disk and both nails used in the mounting thereof will be wholly concealed.

For hanging the lamp from a chair back or any other similar support, the operator simply pivots the spring hook 35 outwardly about the rivet 36 which connects it to flange 33. In this position the spring hook 35 may readily be engaged over any such object as rail 38 (Fig. 5), thereby to support the disk 27, with respect to which the lamp base 16 and lamp are pivotally adjustable to the desired position.

However the lamp is supported or mounted, the shell and socket are pivotally adjustable on the standard 14 to any desired position respecting the base. The electrical connections do not interfere with such adjustment inasmuch as the cord 40 leading to socket 17 does not pass through the standard but directly enters shell 16 through a suitable opening provided therein at 39.

The lamp as disclosed is not only light and conveniently adjustable, but is well adapted to be held in the hand for manipulation of the rays emanating from a bulb mounted in the socket thereof. It is further to be noted that the pivotal adjustment of the socket shell respecting the standard is upon an axis substantially at right angles to the axis upon which the standard is pivotally adjustable respecting the mounting element 27. Appropriate manipulation of the parts about these axes at right angles to each other enables the socket to be given substantially universal adjustment respecting the mounting element whether such mounting element is suspended or permanently fixed to the wall, or whether it is hooked to a support as shown in Fig. 5.

While the invention has been disclosed with reference to its preferred embodiment in a portable lamp it will be understood that various features of the invention are not limited to lamp usage.

We claim:

1. In a device of the character described, the combination with a hollow base having elongated side margins and a boss mounted within said base in a central location between such margins and within the hollow thereof, of a mounting element provided with a pivotal connection to said boss and having at least one mounting aperture, and a tab provided with a second aperture and located at such a distance from the pivotal connection aforesaid that it is normally housed within said base but may be positioned by relative rotation of the mounting element in its own plane respecting the base to project beyond one of the margins of the base, the base being elongated in one direction from the boss, whereby to be adapted to receive and house the tab when the element is rotated to align the tab with the direction of elongation of the base.

2. The combination set forth in claim 1 in further combination with a spring hook pivoted to the mounting element upon an axis generally radial with respect to the aforesaid pivotal connection, said hook being movable upon its said pivot between a retracted position in which said hook lies substantially in the plane of said element and an operative position in which said hook projects from the plane of said element,

said hook being adapted in its said retracted position to lie within the cavity of said base for movement with said element about the pivotal connection of said element with said boss.

3. In a device of the character described, the combination with a lamp base and a lamp socket mounted thereon, of a boss disposed within the base and provided with a transverse bearing surface, a mounting element disposed beneath the lamp in engagement with the said boss surface base and provided with a fastener securing it to the boss and providing pivotal connection thereto, said element comprising a disk in said base, said base being provided with a cavity about said pivotal connection, a flange mounted on the disk and projecting into the cavity, the disk having an opening to which said flange is contiguous, and a spring hook pivoted to the flange upon an axis including the disk pivot and normally disposed in the opening of the disk and within the cavity of the base for movement with said disk about said pivotal connection, said hook being movable pivotally respecting the disk to a position of projection therefrom for engagement with suitable support.

4. The combination set forth in claim 3 in further combination with a pivotal connection between the lamp socket and base upon a different axis from the axis of said pivotal connection between the base and disk, the combined effect of the pivotal adjustments on the respective axes affording universality of adjustment of said socket respecting said disk.

5. The combination with a base and a lamp socket, of a socket support comprising a hollow shell provided with a slot, said lamp socket being disposed within the shell and said base having a standard extending through said slot into the shell and provided with a pintle spanning the standard and the shell and upon which the shell is hingedly movable respecting the base.

6. The combination set forth in claim 5 in which the lamp socket is provided with a bracket having an aperture through which such pintle extends and whereby said socket is retained within the shell.

7. In a device of the character described, the combination with an apertured standard and a pintle extending transversely therethrough, of a shell having a slot into which said standard projects, said shell having apertures engaged on said pintle for pivotal movement respecting the standard.

8. The combination set forth in claim 7 in which said pintle is embraced by a spacing sleeve fitted between said shell and one side of said standard and a spring encircling said pintle between said shell and the other side of said standard.

9. The combination set forth in claim 7 in which said pintle is embraced by a spacing sleeve fitted between said shell and one side of said standard and a spring encircling said pintle between said shell and the other side of said standard, together with a socket member within said shell and fitted thereto for movement with the shell about the pintle, said socket member having a bracket with an aperture through which said pintle extends, said bracket being interposed between said spring and said standard, and the bracket member and standard having coacting friction faces.

10. In a lamp, the combination with a slotted base, of a sheet metal standard having tongues projecting through the slot and oppositely flanged

and provided with connection interiorly to said base, a shell having a socket receiving portion and provided elsewhere with a slot into which said standard extends, a pintle spanning the shell and traversing the standard whereby to provide a pivotal connection between the shell and standard, and a socket within the shell provided with an apertured connector through which said pintle extends whereby said pintle holds said socket within the socket receiving portion of the shell.

11. The combination set forth in claim 10 in which said pintle is encircled by a spacing sleeve between the standard and one side of the shell and a compression spring between the standard and the other side of the shell.

12. The combination set forth in claim 10 in which said pintle is encircled by a spacing sleeve between the standard and one side of the shell and a compression spring between the standard and the other side of the shell, said bracket being interposed between the spring and the standard, and the bracket and standard having complementary friction bearing faces urged into operative friction engagement by the compression of the spring.

13. In a lamp of the character described, the combination with an elongated base comprising a shell having marginal flanges downwardly directed and provided, intermediate the sides of the base and closer to one end than the other thereof, with a mounting boss, of a disk provided with a fastener connecting it to the boss substantially midway between the sides of the base, said disk having a tab projecting radially to a distance sufficiently great to project from the end of the base closest to the boss when the tab is rotated into registry with such last mentioned end, the tab being provided with a mounting aperture adapted in the position last mentioned to project from the last mentioned end and in another position to be housed within the base, a standard

connected with the base at the end thereof most remote from the boss, a pintle bolt extending through the standard in a direction transversely of the base, a slotted shell in which the end of the standard is disposed, said shell having portions engaged on said bolt for pivotal movement respecting the standard, a lamp socket in said shell and means for resisting free pivotal movement of said shell respecting said standard, whereby to maintain said shell and socket in adjusted position respecting the standard.

14. The combination set forth in claim 13 in which the means for resisting pivotal movement of the shell respecting the standard comprises a thrust-sleeve confined between the standard and one interior side of the shell and through which said pintle bolt extends and a spring encircling said bolt and confined between the shell and the standard whereby to maintain frictional pressure between the standard and the end of the sleeve.
